UNITED STATES PATENT OFFICE.

ADOLPH C. RECKER, OF OAKVILLE, CONNECTICUT, ASSIGNOR TO THE CHASE COMPANIES, INC., OF WATERBURY, CONNECTICUT, A CORPORATION.

SOLDERING-WIRE SPOOL AND FLUX-CONTAINER.

1,366,278.

Specification of Letters Patent. Patented Jan. 18, 1921.

Application filed December 26, 1919. Serial No. 347,625.

To all whom it may concern:

Be it known that I, ADOLPH C. RECKER, a citizen of the United States, residing at Oakville, in the county of Litchfield and 5 State of Connecticut, have invented a new and useful Improvement in Soldering-Wire Spools and Flux-Containers; and I do hereby declare the following, when taken in connection with the accompanying drawings 10 and the characters of reference marked thereon, to be a full, clear, and exact description of the same, and which said drawings constitute part of this application, and represent, in—

15 Figure 1, a view in side elevation of my improved soldering-wire spool and flux-container.

Fig. 2, a view thereof in vertical central section.

20 Fig. 3, a detached view in elevation of the combined stopper and spatula.

My invention relates to an improved soldering-wire spool and flux-container, designed to be used for the convenience of all 25 persons who have occasion to do soldering operations, particularly in a small way; the object being to produce for the purpose described, at a very low cost, a simple, compact and convenient carrier for the wire 30 and flux.

With these ends in view, my invention consists in a combined soldering-wire spool and flux-container having certain details of construction as will be hereinafter described 35 and pointed out in the claim.

In carrying out my invention as herein shown, I employ a spool 2 having a concentric flux-containing cavity 3 and formed at its opposite ends with flanges 4 and 5 between which soldering-wire 6 is wound in 40 superimposed coils. The open upper end of the cavity 3 is closed by a suitable stopper 7 mounting a spatula or spreader 8 which enters the flux 9 in the cavity the bottom of 45 which is closed by the lower end of the body

of the spool. The wire may, of course, be coarse or fine in diameter and of any desired length, while the amount of flux may be proportioned to the amount of wire so that there will be no waste.

My improved carrier, as described, provides a simple, convenient, and compact method of equipping a soldering outfit with wire and flux which, as they must be used at the same time, are conveniently combined 55 in one package. In soldering, one or two coils, more or less, of the wire are unwound. The spool held in the left hand, then becomes a handle, as it were, by which the free end of the wire is guided and directed to 60 the point of soldering. With the spool held in the left hand, and used to guide the free end of the wire, the right hand is used to hold the stopper for the application of the flux with the spatula, which is then returned 65 with the stopper to the spool after which the right hand manipulates the soldering iron or is free to work with the flame in flame-soldering.

I claim:

As a new article of manufacture, a combined soldering-wire spool and flux-container, comprising a wooden spool formed at its opposite ends with concentric flanges between which soldering-wire is wound in 75 superimposed coils and one end of the said spool being entered by a concentric flux-containing cavity the bottom of which is formed by the opposite end of the spool, and a stopper adapted to fit into and close 80 the open end of the said cavity and mounting a spatula or spreader extending thereinto.

In testimony whereof, I have signed this specification in the presence of two sub- 85 scribing witnesses.

ADOLPH C. RECKER.

Witnesses:

JOHN S. MEAGLE,
B. C. ATWOOD.
